UNITED STATES PATENT OFFICE

ROY EMERY, OF BROOKLYN, NEW YORK

SELECTIVE MECHANISM

Application filed December 22, 1925. Serial No. 77,092.

This invention relates to selective mechanism of the same general character as set forth in my application for Letters Patent filed June 23, 1925, Serial Number 39,155, and is intended to be employed in like manner and for like purposes as the selective mechanism set forth in my previous application.

The object of this invention is the same as that of the applicant in said previous application, and further objects are as follows:

- 10 1. To provide a selective mechanism as described and shown which may be constructed and which will operate to, the attainment of the objects specified, with a comparatively small number of parts.
- 15 2. A further object is to provide a selective mechanism in which a more accurate and positive action is possible.
- 20 3. A further object is to provide a selective mechanism with a magazine unit and a keyboard unit wherein electrical means may be employed instead of mechanical means for transmitting movement from the keyboard unit to the magazine unit.
- 25 4. A further object is to provide a selective mechanism of the character described wherein a minimum of power will be required to actuate the keys of the keyboard unit in order to operate the selective mechanism.
- 30 5. A further object is to provide a clutch mechanism normally motionless, which may be instantaneously brought into engaged relation with continuously moving parts and thereby insure instantaneous and rapid movement of the normally motionless parts; as connecting the selective cam rods of the magazine unit with continuously rotating gears; by an improved form of clutch.
- 35 6. A further object is to provide a keyboard unit with an electrical switch mechanism whereby a plurality of switches are provided, any one of which, or any combination thereof may be actuated in unison, whereby each switch will close a circuit, and thereby
- 40 45 actuate an electromagnet provided, for actu-

ating the clutch mechanism of the transmission unit, so as to actuate the cam rods of the magazine unit, and so said electro-magnets will be actuated singly or in different combinations in unison corresponding with the combinations of the switches of the keyboard unit.

7. A further object is to provide a clutch which may be actuated by electrical means, spring means and cam means in such a manner that it will act quickly and certainly and require a minimum of power to actuate the same, both in actuating the clutch engaging means and in the release of the clutch.

8. A further object is to provide an electromagnet to be employed in this selective mechanism embodying the lever principle, and at the same time providing a lever of such character that the end thereof most remote from the fulcrum will be nearer to the core of the magnet than the intermediate portion of the lever, so that when the lever swings back, creating the necessary gap between the lever and said core, to break the circuit and provide necessary movement of the parts, the extreme end of the lever will be in closer proximity to the core than the intermediate part thereof, thus insuring attractive force upon the lever by magnetic action sufficient to move the lever, and also insure magnetic attraction upon the end of said lever, thus exerting the maximum force through the lever.

9. A further object is to provide a selective mechanism, embodying a plurality of selective rods of an improved type for actuating releasing means of the escapement mechanism.

10. A further object is to provide an escapement of an improved type for a magazine whereby matrices or other units may be released or controlled with certainty and instantaneously, and with slight effort by the operator.

11. A further object is to provide a trip mechanism for a clutch, wherein said trip

50

55

60

65

70

75

80

85

90

is controlled by electrical and mechanical means each co-acting with the other so as to produce the result to be attained.

12. A further object is to provide a novel form of spring trip for actuating the releasing means or escapement of a magazine in which selective mechanism is employed.

13. A further object is to provide a keyboard mechanism embodying a plurality of movable blades and a plurality of keys; a plurality of clutch elements each adapted to be actuated by one of the keys, and each having a series of extensions thereon adapted for engaging one or more of said blades; and means for shifting one or more of the blades whereby the clutches may engage the blades in different combinations when one or more blades are shifted, so that the movement of one key will shift one blade, and another key will shift two blades, as required to make the shift from the normal position of the blades to the shifted position, or from the shifted position to the normal position.

14. A further object of the invention is to provide a selective mechanism comprising a magazine unit and a keyboard unit wherein the magazine unit is selectively actuated by selective mechanism of the keyboard unit and in which the motive force is transmitted through flexible cable from the keyboard unit, making it possible to adjust the keyboard unit and locate it to suit the convenience of the operator, relative to the magazine unit, and in no manner interrupt the operation of the mechanism.

15. And a still further object is to provide a selective mechanism having a magazine unit and a keyboard unit embodying a plurality of cam rods in the magazine unit rotatably held in bearings and rotatable singly or in different combinations as required to actuate the escapement, or releasing means, but which are normally at rest, and a series of normally rotating gears, one gear corresponding with each of said rods and clutch means whereby any one of said rods may be thrown into engagement with its respective gear, either singly or in different combinations of any number in unison; and each rod so engaged will make one revolution and stop, as required to actuate the escapement means of the magazine.

16. A further object is to provide a selective mechanism of the character described, in which a minimum of physical exertion is necessary to actuate the mechanism and wherein a maximum degree of certainty and speed will be insured in the operation; in which a minimum number of parts will be employed thereby reducing cost of manufacture and providing a mechanism which will economize labor, and which is more convenient for use, and more adaptable to the needs and requirements of the industry to which it appertains.

17. A further object is to provide selective mechanism whereby it is possible to dispense with a separate key for each of the standard ligatures, except "ff," which is accomplished by touching the two keys for the letters of the ligatures, thereby actuating the escapement for the required ligature matrix without actuating the escapement for the respective letters of the ligature.

18. A further object is to provide a shift key mechanism whereby any desired shift may be made at any time by touching only one shift key.

19. A further object is to provide a selective mechanism with a keyboard unit in which the clutch elements or a part thereof have removable fingers, extensions or clutch elements upon the weight or clutch members; or clutch elements made permanently upon the clutch members, with but a limited number of fingers, extensions or clutch elements thereon for engaging a certain number of the blades or combinations of blades.

20. A further object is to provide extra keys which may be changed at the will of the operator to effect the release of special characters that are run into the magazine for special work, such as accented characters, fractions, advertising figures, &c.

21. A further object is to provide tripping means connecting the blades of the keyboard mechanism with the clutch releasing means of the transmission mechanism which controls the cam rods of the magazine unit, whereby the release is tripped by a simple mechanical device.

22. A further object is to provide direct connection between the blades of the keyboard unit, and the trip of the clutches which control the cam rods, whereby the trip of the clutches may be made by a direct pull through a wire or cable or mechanical equivalent upon the tripping means.

With these and other objects in view, reference may be had to the accompanying drawings forming a part of this specification, in which similar reference characters refer to similar parts throughout the several views thereof.

In the drawings Fig. 1 is a plan of the keyboard used in the practice of my improvements in selective mechanism as applied to typographical machines of the class shown and described in Letters Patent No. 436,532 granted September 16, 1890, to O. Mergenthaler; Fig. 2 is a vertical longitudinal sectional view through the keyboard unit of my selective mechanism, taken on line 2—2 of Fig. 1, but including mechanism not shown in Fig. 1; Fig. 3 is a vertical longitudinal sectional view taken on line 3—3 of Fig. 1; Fig. 4 is an elevational view partly in section showing the switch mechanism of the keyboard unit, the line of section of the parts so shown is on the line 4—4 of Fig. 5; Fig. 5 is a

extension 208 with the bearing element 210 which is removably secured by screws 210^a and 210^b. The said bearing members removably holds shafts 201 and 207 in their positions in bearings 211 to 217. When it is necessary to remove the shafts 201 to 207 or any of them from their bearings, the bearing plate 210 is removed and the frame member 110 is also removed, and said shafts 101 to 107 and the parts or shafts into which they are socketed, as stub shafts 201 to 207 may be lifted from their bearings.

Each of the stub shafts 2001 to 207 carries an idle gear as 221 to 227 inclusive, of which the gear 227 is typical, as indicated in Fig. 13. These gears inter-mesh and run constantly in a train and are driven from gear 227, by any suitable means as gear 228, which is so formed and adjusted as to rotate the gear 227, and suitable driving gear 229.

Said gears 228 and 229 may be bevelled or a pulley may be substituted in the place of gear 228.

It will be seen that the cam shafts 101 to 207 may remain at rest while the gears 221 to 227 rotate continuously. To actuate the spring releasing members 1001 to 1090 for ejecting a matrix from the magazine, it is necessary to rotate one or more of the cam rods, or cam shafts 101 to 107. This operation will be presently explained, but in this place it is essential to explain merely the trip mechanism of the transmission unit, corresponding with the transmission unit shown and described in my previous application, (Serial No. 39,155).

In this application as in the previous application there are three co-acting units, the magazine, or escapement unit, the transmission unit and the keyboard unit. In the present application the transmission unit is mounted upon and directly connected with the magazine unit and constructed as a part thereof. The cam rods 101 and 107 belonging to the magazine, or escapement unit, as before explained are provided with angular ends as 101^a to 107^a and said ends are seated in corresponding angular recesses in socket members 201^a to 207^a provided upon the ends of stub shafts 201 to 207. The said stub shafts are socketed at their opposite ends 201^b to 207^b in the idle gears 221 to 227. Each of said idle gears has an extension thereon as 221^a to 227^a which is held in bearings provided in the extension 208 of the frame 108 and the removable plate 210.

Upon the stub shaft 207 a clutch member 237, is splined being one of a series of clutches 231 to 237, not all shown, and upon the idle gear 227 is a mating clutch 227^a. When the clutch is in engagement the clutch member 237 is caused to rotate with the rotating idle gear which rotates continuously.

By the means described the stub shaft 207 upon which said clutch member 237 is splined

is rotated and the cam-rod 107 having its end 107^a seated in the socket member 207^a of the stub shaft 207 is rotated therewith. One or any number of said cam rods 101 to 107 may be rotated when the clutches thereof are thrown into engagement, so as to actuate the required spring releasing member. For example; if one clutch only is engaged only the corresponding cam rod will be rotated, but if any two of the clutches are engaged or any three or any other number, are engaged, then the corresponding cam rods will be rotated accordingly.

To engage the clutches it is necessary to release the trip of the transmission unit 200, which is done by actuating a key of the key board unit 300, hereinafter described.

The trip mechanism comprises the splined clutch members 231 to 237 and other parts shown in Fig. 14 of the drawings. The clutch member 237 is slidably splined upon the stub shaft 207 and is normally held disengaged from the clutch members of the idle gear 227, by the trip 247 of the series, 241 to 247 which trip is pivoted at 247^a and has two pawls 247^b and 247^c thereon. The pawl 247^b engages a lug 237^a on the clutch member 237 whereby the clutch is held disengaged. The trip is released by touching a key of the key board whereby an electric circuit controlling an electromagnet 257, is connected, or closed, said magnet being of a series, 251 to 257, (not all shown). The movement of the magnetic trip overcomes the tension of the spring as 247^d of the series, 241^d to 247^d (not all shown) and releases to pawl 247^b and at the same time the pawl 247^c is moved so as to enter the annular recess or groove 237^e of the clutch 237. The spring 267, of the series 261 to 267, (not all shown) then forces the clutch member 237 towards the idle gear 227, but not far enough to engage the clutch. This movement is instantaneous and the trip member 247 retained by the magnet only so long as the circuit is closed. When the circuit is broken by the releasal of the key of the key board, the trip 247 is instantaneously restored by the spring 247^d. As soon as the trip is restored to its former position the trip pawl 247^c disengages the groove 237^e and thus the clutches 227^a and 237^a are thrown into engagement by the spring 267. The said clutch member is provided with cam means for disengaging the clutch and stopping the rotation of the clutch after a single revolution at the initial or normal position thereof, so that the parts after a single rotation instantaneously come to a stop and are in readiness for being again actuated. The said cam means comprises the cam 237^a and the cam roller 277 of the series 271 to 277, (not all shown) and said cam roller is shown in dotted lines and is supported upon a stud 278.

To carry out the theory of my invention, which is; primarily to provide means where-

sectional view taken on the line 5—5 of Fig. 4; Fig. 6 is a fragmentary sectional view showing details of shifting keys, taken on line 6—6 of Fig. 3; Fig. 7 is a detail fragmentary 5 sectional view taken on line 7—7 of Fig. 3; Fig. 8 is a sectional view taken on the line 8—8 of Fig. 9, showing details of the selective rods and escapement for releasing matrices from the channel of the magazine; Fig. 9 is a 10 fragmentary plan showing details of the selective rods and escapement mechanism as applied to a linotype machine; Fig. 10 is a section taken on line 10—10 of Fig. 9 looking in the direction of the arrow; Fig. 11 is a dia- 15 grammatic view representing the arrangement of the cam elements of the several selective cam rods of the magazine unit of my selective mechanism; Fig. 12 is a transverse vertical sectional view of the keyboard unit 20 showing the selective blade elements, shifting means and indentations of the blades. For clearness in drawing the line of vision is assumed to descend at an angle of 45 degrees, showing two dimensions of the parts; 25 Fig. 13 is a sectional view through the magazine unit of my selective mechanism on line 13—13 of Fig. 14 showing the means of driving the cam units for releasing the matrices of the preferred form of mechanism; Fig. 30 14 is a sectional detail view showing the trip mechanism whereby the cam rods are engaged with the rotating gears so that they are rotated with the rotating gears so as to actuate the spring releasing members and the releas- 35 ing pawl; Fig. 15 is a fragmentary perspective view showing details of construction of the frame for supporting the releasing mechanism of the magazine unit; Fig. 16 is a detail fragmentary view of one of the weights 40 with removable pawls employed for blank keys, wherein the clutches thereof are interchangeable and can be arranged to engage any one or any combination of the blades, at a portion thereof, where the blades are not 45 indented; Fig. 17 is a sectional view in detail of the transmission mechanism, showing a modified form of the means employed for releasing the trips of the clutches which control the cam rods, and showing a direct me- 50 chanical connection with the blades of the keyboard mechanism; Fig. 18 is a fragmentary view showing the end of the keyboard unit in elevation and showing the manner in which 55 mechanical means is employed for imparting movement from the blades of the keyboard unit directly to the tripping means of the clutches as shown in Fig. 17, whereby the cam rods are controlled; Fig. 19 is a fragmentary view showing the rear of the keyboard unit 60 in elevation showing the parts illustrated in Fig. 18 of the drawings, and Fig. 20 is a dia- 65 gram of the electric circuit.

Referring to the drawings forming a part of this specification my improvements in selective mechanism herein described com-

prises; first, selective escapement mechanism; second, transmission mechanism, and third, keyboard mechanism.

In the selective escapement the numeral 100 indicates the magazine unit, and 101 to 107, inclusive are selective cam rods adapted to be intermittently rotated and to actuate the spring releasing members numbered 1001 to 1090 inclusive, only a part of which are shown, they being numbered 1001 to 1010, and in Fig. 14, the spring releasing member shown is 1090. The spring releasing member shown in Fig. 8 may be assumed to be 1001. The cam rods 101 to 107 are rotatably held in bearings in a frame 108 which supports all the parts of the selective mechanism of the escapement and transmission mechanism, and comprises the base section 109 and the removable section 110. At the left are bearings 111 to 117 inclusive, for the ends of the cam rods. The opposite ends of the cam rods are non-circular in cross section, as indicated in dotted lines and are removably seated in correspondingly formed sockets 121 to 127 inclusive on the ends of the shafts 201 to 207 inclusive of the transmission mechanism.

In the frame section 110 there are two transverse bars 110^a and 110^b and in the bar 110^a are provided slots as 1101^a to 1190^a, and in the bar 110^b are provided slots 1101^b to 1190^b, in which are seated the respective ends 1001^a to 1090^a and 1001^b to 1090^b of the spring releasing members 1001 to 1090.

Under the transverse bar 110^a is a removable plate 110^c and superposed upon the bar 110^a is a removable plate 110^d. Under the transverse bar 110^b is a removable plate 110^e, and superposed upon the bar 110^b is a removable plate 110^f.

Said removable plates serve to retain the ends 1001^a to 1090^a and 1001^b to 1090^b of the spring releasing members 1001 to 1090 in said slots 1101^a to 1190^a in the bar 110^a and slots 1101^b to 1190^b in the bar 110^b.

When said removable plates are in assembled relation with the said transverse bars 110^a and 110^b the said slots are enclosed so that recesses are formed to retain the ends 1001^a to 1090^a and 1001^b to 1090^b of the spring releasing members 1001 to 1090. This form of construction is designed so that the slots 1101^a to 1190^a of the bar 110^a and the slots 1101^b to 1190^b of the bar 110^b can be cut directly through the said bars and so facilitate construction of the recesses aforesaid, and so that by removing the superposed plates 110^d and 110^f it is possible to remove any one of the spring releasing members 1001 to 1090, from the frame by lifting the ends thereof from their respective slots, but when the superposed plates are secured in their positions the spring releasing members are securely held in the slots in the said transverse bars.

A further member of the frame 108 is the

by a matrix may be selectively released from its respective usual channel in the magazine by touching a key corresponding with such matrix, when such key is depressed, wherever it may be located in the keyboard, in accord with the most desirable layout of the keys, it is obvious that means must be provided for transmitting movement of the particular key desired to the releasing means of the magazine unit, so that the corresponding matrix will be released from its usual channel when such key is actuated.

The release of the matrix corresponding with the key actuated is accomplished by means of the selective mechanism which comprises first; the key weights numbered 1 to 64 inclusive, counting from left to right; and second; the blades 301 to 307 inclusive; and third; the transmission mechanism hereinbefore described connected with the magazine unit, and fourth; the selective cam mechanism of the magazine unit.

Each of the key weights is mounted so as to be movable vertically in suitable bearings. (See Fig. 2.) In the figure key weight 19 is shown, having an upper extension 19^b and a lower extension 19^a, which are disposed in suitable guides so that the weights may be raised and lowered by the keys of the keyboard 1 to 64 inclusive. The key weights, are all alike in form, except where special key weights may be made as may be hereinafter explained. But the uniform key weights have each a plurality of recesses as 19^c to 19^g inclusive, so that they may be used interchangeably for the key levers, as 15, 16, 17, 18, or 19, and each key weight has a series of extensions thereon as 19^h, 19ⁱⁱ &c. to 19^{vii} for engaging the blades 301 to 307 inclusive or a part of them according to the key and the particular combination of blades actuated by said key. Provision is made however so that each of the key weights will engage, only certain pre-determined selective blades, whereby the required combination of the blades will be engaged and actuated by each particular weight, when elevated by its respective key. A complete table of the combinations is hereinafter set forth as a part of this specification.

It will be obvious that the portions of the blades where they are cut away cannot be engaged by the extensions or fingers of the key weights but will be engaged thereby only where they are not cut away. The object of this provision is; that when any of the blades 301 to 307 are rocked by the key weights the movement will be transmitted through the transmission unit 200 to the magazine, or escapement unit 100 and so actuate the spring releasing mechanism by means of the cam rods 101 to 107, or certain selective number of the said cam rods in order that the matrix in the channel corresponding with the key by which the parts were actuated will

be released from the magazine. Explanation follows.

Thus if one blade only is engaged by the key weight, only that one blade will move, and such movement will be transmitted to but one of the rocking rods, or cam rods of the magazine unit 100; but if two of the blades are engaged by the weight that is actuated then that movement will be transmitted to two of the rocking rods or cam rods of the magazine unit.

It should be remembered that the selective process is as follows: By removing from the blades the part thereof which might be engaged by the fingers or extensions of the key weights when it is desired that the movement of the key weight should not actuate the particular blade; and on the other hand, where it is desired to actuate a certain blade by a certain key weight and connecting key the portion of the blade contiguous, remains so as to be engaged by the contiguous finger or extension of the key weight adjacent thereto.

To transmit selectively the movement of one of the keys of the keyboard through the transmission unit to the selective mechanism of the magazine unit, electrical means is employed to actuate a plurality of electro-magnets hereinbefore described whereby the trip mechanism described is actuated.

The electrical means employed comprises a plurality of circuit closing switches provided upon and actuated by each of the blades 301 to 307, shown in Fig. 4 and Fig. 5 of the drawings.

Each of said blades 301 to 307 has an extension as 311 to 317 and a switch as 321 to 327, is mounted thereon so that it will be moved in an arc whenever the blade is rocked. The ends of said extensions are angularly formed, and insulating sleeves 331 to 337 are disposed within angular opening in the switches, then the sleeve is disposed upon its respective extension. The said sleeves abut against an insulating plate as 341 to 347, so that the switches are fully insulated from the keyboard mechanism and the rocking blades. To each of the switches, is connected a wire as 351^a to 357^a indicated in dotted lines and communicating with magnets 251 to 257 respectively.

Each of the switches is provided with a spring circuit closing element as 371 to 377 whereby the circuit may be closed with but slight movement of the rocking blades. Each of the switches is designed to connect with a universal insulated bar as 380 which is provided with extensions 381 to 387 to serve as contacts and which is mounted removably upon guides as 380^a and 380^b. The bar 380 is also constructed so as to contact with the universal insulated contact 388 having the binding post 389 securing the universal wire 390 which connects with the battery 390^a. Another wire 390^b connects the battery with the

binding posts as 251^b to 257^b of the electromagnets 251 to 257 (Fig. 20).

It will be obvious that when any one of said switches, 321 to 327 contacts with the universal bar 380 said bar will be raised so as to contact with the universal contact 388 so that the electromagnet connected therewith will be actuated and the trip mechanism thereby released so that the corresponding cam rod will be rotated by means of the clutch connected therewith. Accordingly, since the said switches, magnets and trips are designed and adapted to act either singly or in combinations of two to seven units, it will be seen that correspondingly with the number of rocking blades and connected switches that are actuated the connected magnets, trips and clutches, will be actuated singly or in combinations of two to seven units.

Thus by the selective mechanism of the keyboard unit, the selective mechanism of the transmission unit or tripping means is selectively actuated, so that the selective cam rods are actuated, singly or in combinations of two to seven, so that by touching a certain key of the keyboard unit, the required spring releasing member of the magazine unit is actuated so that a matrix corresponding with the character of the key actuated will be ejected from the magazine.

The escapement employed in the selective mechanism may now be described. The spring releasing members 1001 to 1090 are represented in Fig. 8 by the member numbered 1001 and in Fig. 9 by members 1001 to 1010 inclusive. The said spring members are firmly held by extensions as 1001^a and 1001^b in slots in the frame 108 and are normally held in elevated position against the force of the spring elements 1001^c and 1001^d as shown in Fig. 8 by one or more of the cam rods 101 to 107. In Fig. 8 cam rod 101 is shown holding spring member 1001 in the elevated position. The spring member 1001 is actuated only when cam rod 101 only is actuated. The cam element is lowered by the rotation of the cam rod and there being no other cam element to support the spring member 1001 it is released and lowered by its own spring power.

The escapement pawl 1201 of the series 1201 to 1290 is actuated by the spring releasing member so as to eject a matrix from the magazine channel controlled thereby.

In case two or more of the cam rods rotate in combination to release the spring releasing member each of the cam elements of such combination is formed and normally disposed as the cam element of cam rod 101 in Fig. 8, that is to say; it is oblong in cross section and is perpendicular to the plane of the magazine and the said several cam elements always rotate in unison when the spring releasing member thereabove is to be actuated, so that each of the cams in the combination

are rotated in unison, thereby permitting the spring releasing member to act.

And again; if all of the said perpendicular cam elements under a spring releasing member are lowered, but one or more of the cam elements such as shown in Fig. 8 in rods 102 to 107 inclusive rotate at the same time, still the spring releasing member cannot act, since the body of the rod as 102 to 107 one or more of which may be rotated will support the spring releasing member, and prevent it from being lowered by its own spring power.

For example; the cam element of cam rod 101 may be lowered by the rotation of cam rod 101 alone, but if at the same time cam rod 102 or any other, others or all of the other cam rods are rotated the spring releasing member cannot act because it is supported by the peripheral surface and body of such cam rods, one or more, 102 to 107, which may be rotated.

The cam element of rod 101 when rotated is at the minimum elevation during 180 degrees of its revolution thus permitting the maximum descent of the releasing member during one half of its revolution.

In the case of each of the spring releasing members the cam combinations by which they are controlled must have one or more of said cams normally in engagement therewith, and in all combinations but the one described and shown in the drawing Fig. 8, there are two or more of such cam elements normally in engagement with the spring releasing member, and the others in said combination are disengaged normally. The cam elements normally engaged are formed and disposed as cam element 101 and these normally disengaged are formed and disposed as cam elements 102 to 107 inclusive, and in order that the spring element may act, those engaged and no others are rotated, but when any one or more of those normally disengaged are rotated the spring releasing means cannot act. Furthermore if one or only part of the cam elements normally engaged in any combination rotate and not all, yet those not rotating still engage the spring releasing means and prevent it from acting.

The matrix release proper, consists of a pawl as 1201 of the series 1201 to 1290. These are mounted upon a rod, 1109 held upon the magazine 100. The pawl comprises a weighted extension 1201^a which normally engages the ear of the matrix first to be ejected and is normally held in engagement therewith by the weighted portion 1201^b. Said pawl has an arm 1201^c which is normally disengaged from the matrix next to the first matrix, but when actuated by the arm 1001^c of the spring releasing member 1001 it is lowered so as to contact with the toe of the second matrix and at the same time the extension 1201^a is disengaged from the ear of the first matrix so that the first matrix is released

and the impact of the arm 1201^c upon the toe of the second matrix forcibly drives the second matrix forward against the first matrix which is thus ejected from the channel of the magazine. There is an extension 1201^d upon the arm 1201^c of said pawl 1201 which forms an inclined plane against which the ear of the second matrix will impinge when the said arm 1201^c is lowered in the manner described, and thus the force exerted by the weight of the matrices in the channel against the second matrix will cause the ear of the second matrix to impinge against and elevate the arm 1201^d and restore the extension 1201^a to the normal position and thereby engage the ear of the second matrix as it moves into the position of the first matrix in readiness to be ejected. The weighted end 1201^b of the pawl 1201 aids in restoring the pawl to its normal position in case the weight of the extremely thin matrices in a channel does not afford sufficient pressure to lift the said arm 1201^c and insure the return of the extension 1201^b to its normal position so as to engage the ear of the first matrix.

The arm 1001^a of the spring releasing member 1001 serves merely to actuate the said pawl 1201 and is instantly restored to its normal position by the rotating cam rods and cam elements thereof and the pawl 1201 is automatically restored to its normal position by said weighted portion 1201^a and by the pressure of the matrices in the channel in the manner above described.

There are shown in the drawings sixty-one keys. Each of said keys actuates one of the key weights, which are numbered from 1 to 61, consecutively from left to right. The key weight shown in Fig. 2 is numbered 19, and is actuated by the key carrying the asterisk, as shown in the keyboard layout in Fig. 1, and indicated as key lever 19.

The key weights shown in Figs. 2 and 5 are of a modified form, all being of the same shape as though cast from one mold or cut by one die. Each key weight, as 19, has an upper extension, as 19^b, and a lower extension, as 19^a, which are held in suitable guides secured to the frame 300 of the keyboard mechanism. Each key weight has a series of recesses, as 19^c, 19^d, 19^e, 19^f, 19^g and 19^h, and the recess 19^c of key weight 19 is engaged by the key lever 19. Accordingly each key lever engages in a recess of one of the key weights described. On the key weights, as 19, there is a plurality of fingers or extensions designated 19^{-I}, 19^{-II}, 19^{-III}, 19^{-IV}, 19^{-V}, 19^{-VI}, 19^{-VII}, 19^{-VIII}. The said extensions are adapted for engaging the rocking blades numbered 301 to 308 inclusive in the manner described in another part of the specification, in various combinations. Said key weights are also described and shown in my pending application, Serial No. 39,155.

In Fig. 16 is shown a modified form of the

key weights in which the fingers or extensions are removably held thereon. The key weight is designated as W-1 and the extensions are numbered from 1 to 7. When using this form of the key weight, the proper connections to actuate the required combinations of rocking blades may be obtained by removing from a weight such fingers or extensions as it is not desired to use. Thus, if extensions 1, 3, and 6 are removed, rocking blades corresponding with extensions 1, 3, and 6, will never be actuated by the weights from which they are removed. With this form of key weight, the construction of the blades may be much simplified and any particular key weight may be so changed by changing the extensions thereof so as to actuate a different combination of rocking blades.

It will be obvious that the rocking blades that are not shiftable may be plain blades that are not indented. When this form of keyweight is used the form of the shiftable blades may be much less simple than when the keyweights with fixed extensions are employed.

One form of means for locking the key weights is shown in Fig. 2 in dotted lines and in Fig. 3 in solid lines. A shoulder, as 19ⁱ, is provided upon each of said key weights, and a semi-cylindrical bar 300^x, is revolvably held thereabove, normally in a disengaged position, and in cross section being horizontally disposed, as shown in Figs. 2 and 3. When it is desired to lock the key weights against movement the said bar 300^x is turned by means not shown, 90 degrees or more so that the cylindrical surface engages the shoulders, as 19ⁱ, of all the keyweights and prevents movement thereof.

In Figures 4 and 5 I have shown the preferred form of my locking means, as described hereinafter.

Referring to Fig. 5, 308 indicates the locking member corresponding with the blade 108 in Fig. 12 of the drawings also shown in Fig. 2. The blade is rockingly held in contact with the key weight extension 19^{VIII}, and is movable with each movement of any of the weights, being a solid blade without any notches therein. Said blade 308 is normally held by a spring 308^a in the position shown in Fig. 5 but may be shifted to the left so that the pawl 308^b will engage the recess 308^c in the plate 308^d. The shift is made by the cam 308^e, which is rotatably held upon the extension of said blade, the movement being imparted by the button 308^f. Said cam engages the member 308^g which is keyed to the extension of said blade and has a lug, 308^{g2} which impinges against a lug 308^h so it cannot rotate, but is free to move laterally to the left and thus bring the pawl 308^b into the recess 308^c so that the blade cannot be moved by the weight, thus a lock is provided, which pre-

vents the movement of any key of the keyboard.

In my previous application hereinbefore mentioned, I have shown and described shifting blades, whereby I am enabled to increase the number of combinations obtainable with a limited number of blades. In this application I employ the same principle, but the shifting mechanism herein shown is of a modified form, and is considered herein as the preferred form thereof.

Two forms of shifting mechanism are shown in this application. In Fig. 12 the shifting mechanism is similar to that shown in my before mentioned previous application.

The rocking blades 306 and 307 are shiftable in their bearings. They are held normally at the extreme right by means of springs 306^b and 307^b, which engage collar members 306^a, 306^{aa}, and 307^a. The said rocking blades are moved to the left when desired, by key levers *k*¹¹ and *k*¹², portions of which are shown. The movement is adjusted by means of set screws, as 306^c and 307^c, held in the support 300^a.

The key lever *k*¹¹ is adapted for shifting both blades 306 and 307, while the key lever *k*¹² is adapted to move but one blade, 306.

The preferred form of my shifting mechanism is shown in Figs. 1, 2, 3, 6 and 7 of the drawings. The blades 306 and 307 may be shifted as follows: Upon the blade 306 is rigidly secured a bearing 306^a having a lug 306^b shown in Fig. 7, which is disposed between the arms of a substantially U-shaped lever 306^c held upon a rod 306^d. A spring 306^e normally holds said shifting blade 306 in its normal position at the extreme right.

Upon the blade 307 is rigidly held a bearing 307^a having an extension 307^{a2} slidably engaging the extension of the blade 306. On the bearing 307^a is a lug 307^b disposed between the arms of a substantially U-shaped lever 307^c held upon the rod 307^d, and a spring 307^e holds said blade 307 normally at the extreme right. Set screws 306^f and 307^f afford adjustment for said blades and suitable lock nuts as 306^g and 307^g are provided to secure the set screws in the desired position. When the blades are held in their normal position shifted to the right, similar set screw and lock nuts to secure them may be provided at the opposite ends of the shiftable blades, but these are not shown in Fig. 5 of drawings. But it will be obvious that by the means described perfect adjustment of the position of the shifting blades can be obtained. It is contemplated that similar adjustment may be provided for the other blades which are not shiftable, to insure perfect adjustment of the notches thereof with the extensions of the key weights, should refinement of adjustment prove necessary in the practice of my invention.

To actuate the said shifting means, rocking keys 306^h and 307^h are provided upon the rods 306^d and 307^d said rocking keys are rigidly held upon said rods and serve to move the U-shaped levers as 306^c and 307^c. Pawls 306ⁱ and 307ⁱ engage shoulders as 306^j and 307^j upon spring members 306^k and 307^k, (see Fig. 6). Thus by pressing the button at the right of key 307^h the pawl depresses the spring by cam action and forces it to the left of the shoulder 307^j. The action is the same if it is desired to shift the blade 306. In Figs. 3, 6 and 7, the parts are shown in the shifted position and both of the blades are shifted to the extreme left. As above stated the springs normally hold the shiftable blades in their extreme position at the right. It is designed to move one of the blades or both of them to the left or shifted position by touching a single key or single operation; or when both are in the shifted position to reverse the operation and restore by a single operation, one or both of said blades to their normal position, that is by touching a single key.

This object is attained in the manner described as follows: In Fig. 7 the blades being in the shifted position, that is, to the left; blade 307 may be restored to the normal position by depressing the key designated as S C rocking key 307^h. For this purpose the lever 307^c moves the bearing 307^a to the right and the spring restores the blade 307 to its normal position. Blade 306 remains in the shifted position until key L C of rocking key 306^h is depressed when the lever 306^c throws the bearing 306^a to the right and restores the blade to its normal position. But if in the first place it is desired to restore both blades 306 and 307 to the normal position, this may be done by depressing key button L C of rocking key 306^h and then both of the blades 306 and 307 are restored simultaneously to the normal position, by the pressure of the bearing 306^a against the extension arm 307^{a2} of the bearing 307^a, thus throwing the blade 307 to the right with the blade 306.

To shift the blade from the normal position the action is reversed and the key buttons on the left of the rocking keys are actuated. It is possible to shift the blades singly if the left key button of rocking pawl 306^h is depressed, and then the left key button of rocking key 307^h is depressed; but to shift both at once to the left the left key button of rocking key 307^h is depressed and this brings the extension 307^{a2} of bearing 307^a into action so that it bears against the bearing 306^a on the blade 306 and both blades are thereby shifted simultaneously to the left.

In Fig. 12 a modified form of the shifting means is shown, whereby the shiftable blades may be shifted singly or simultaneously, as

hereinbefore described, but the shifting keys are designed upon principles shown in my before mentiond previous application.

To facilitate the work of the examiner a table has been prepared same being hereto annexed, and designated as Table 1, serving to explain in detail the method and means by which the keys of the keyboard mechanism, control the releases for corresponding matrices in the magazine of the linotype machine and which sets forth fully the various combinations of the parts by which the characters of the standard linotype machine may be released from the magazine combination.

The said table is arranged in alphabetic order; each letter is considered in three forms, and the data for each of said forms is set forth in three lines. The characters of the keys are given in the first column.

The number of the keys are given in the second column.

The first letter, "a" is considered, first as "lower case," second as a "small capital" and third as a "capital." Each letter of the alphabet is considered in the same manner.

The number of the key in its numerical order from left to right is indicated by the numbers in the second column, as shown in Fig. 1 of the drawings.

The next seven columns show the functioning of the seven blades of the keyboard mechanism and show which of the blades act for the releasal of each letter or character. By following the movement through the transmission mechanism to the magazine unit, it is possible by the aid of this table to ascertain which cam rods act, and which spring releasing members are actuated and from which channel the matrices will be released when a particular key is depressed by the operator.

The last column in the table contains the number of the channel from which the matrix will be discharged when the key controlling it is actuated.

The columns numbered from 301 to 307 contain ciphers and "x's." The ciphers indicate that there is no contact of a weight extension with a blade and the "x's" indicate that the weight contacts with the blade and that blade is not cut away or indented at the point where the weight corresponding with the number of the key in the second column is in apposition thereto.

For example lower case "a" is obtained by the "a" key, (key No. 10—2nd column). Key 10 actuates blades 303 and 304 for lower case "a". This is indicated by the "x's" in the first line of the table, at said columns 303 and 304. The ciphers in columns marked 301, 302, 305, 306 and 307 in the first line of the table show that only blades 303 and 304 are actuated for releasing lower case "a" from the magazine. The last column indicates that the lower case "a" matrix will be

released from the 3rd channel of the magazine.

By reference to the layout of the keyboard in Fig. 1, the character of the key will be found on each key and the numerical order or position of the keys employed in the second column of Table 1, is above the upper left corner of the key button.

By referring to Figs. 11 and 12, the table may be further explained. In Fig. 11, the vertical lines numbered from 1 to 90 indicate the number of the channels of a standard magazine, and the characters thereunder the character of the matrices in the respective channels.

It will be observed that two characters occur under some of said vertical lines which indicates that two letter matrices are employed for such channels. The circles at the intersection of the said vertical lines numbered from 1 to 90 and the broken horizontal lines numbered 101 to 107 inclusive indicate the cam elements which act in order to release the matrix from the channel corresponding with the line with a given number.

Thus lower case "a," is carried in channel number 3, see Fig. 11, and the cam elements of cam rods 303 and 304, when acting simultaneously and while no other cam rods are actuated will actuate the spring releasing member 1003 and thereby actuate the pawl 1203 and eject the matrix for lower case "a".

Referring to Fig. 12 of the drawings, it will be seen that a plurality of blades 301 to 307 are shown. Each blade has indentations and across said blades vertical dotted lines are drawn which are numbered from 1 to 61 at the upper part of the figure. These lines indicate the position of the key weights, all of which are alike numbering 61 in all.

The characters on the keys by which the respective key weights are actuated are shown above the numbers designating the vertical dotted lines, and the indentations in the blades, 301 to 307, show the recesses in the blades and the extensions thereof; the recesses indicating that where there is a recess, as dotted line 10°, "A" key, there are recesses in all blades but 303 and 304, so when the key weight number 10 is actuated by key "A" the extensions of said keyweight, which are seven in number can engage only blades 303 and 304, because the other blades as 301, 302, 305, 306 and 307 are all recessed at dotted line 10° and character "A". This corresponds with the explanation given of the table to

which reference may now be had to check up the method. The same rules apply to each letter or character of the keyboard, and the operation may be checked up from the said Table 1, and Figures 1, 11 and 12 of the drawings.

A novel method of releasing ligatures is provided, whereby the operator, may release the ligatures of, "fl", "ffl", "æ", "œ", "fi", and "ffl" by touching the two keys of the keyboard,

in the ligature, thus affecting a combination which will release the ligature desired from the channel in which it is carried. These are also shown in Table 1, and may be checked up with the drawings in the manner hereinbefore described.

The numbers at the right of the key buttons in Fig. 1 indicate the channels from which the matrices will be released when the key is employed, and indicate the difference when the shifting blades 306 and 307 are shifted from the normal.

It will be seen that for all the letters of the alphabet but "x" and "z" the same key may be used, for three operations, viz.: to release lower case letters or matrices, small capital matrices and capital letter matrices.

When the shifting blades are both in normal position (see Table 1), lower case "a" is released from channel 3 of the magazine, and only blades 303 and 304 are actuated. Compare Fig. 12, line 10^a, key character "A" and it will be seen that the blades 306 and 307 are recessed when in their normal position, so that the extensions on weight 10 will not engage the said blades 306 and 307, but will only engage the blades 303 and 304 aforesaid. The uppermost number at the right of key "A" indicates the channel from which lower case "a" is released, when the shifting blades 306 and 307 are in their normal position.

The third number at the right of key "A" indicates the channel from which a capital "A" will be released when both of the shifting blades 306 and 307 are shifted. Compare with Fig. 11, in which capital "A" occurs at the vertical line number 63, the third number at the right of the key "A" is 63 and from channel 63, (see Fig. 11, and Table 1) the capital "A" matrix is released. To release capitals key button "C" of the rocking key 307^b is depressed which shifts both of the shift blades 306 and 307 as set forth.

The second number at the right of the letter keys indicates the number of the magazine channel from which small capitals are released. Again taking the letter "A" for example; the second number at the right of the key button "A" is 39, and by reference to Fig. 11, it will be seen that the small capital "A" is on the line numbered 39. (See also Table 1 last column).

By reference to the said table, line 2, therefore, under the blade number 306, it will be seen that there is an "x" which indicates that shift blade 306 is actuated by key number 10, (see column 2 of Table 1). For all small capitals only one of said shift blades is used, i. e., shift blade No. 306. Thus small capitals are obtained by the letter key of the small capital required when blade 306 alone is shifted. This is accomplished by depressing the key-button marked "S C" of rocking key 306^b.

Referring to Table 1, it will be seen that there is but one channel number (last column) for all characters but the letters of the alphabet. This is because the matrices therefor are found in but one style, there being no capitals or small capitals thereof; while each of the letters of the alphabet must be supplied in three styles, as lower case, small capitals and capitals. Therefore there must be three channels for each letter, but one channel only is required for numbers, trade signs, punctuation marks, points &c. See Fig. 11.

In Figure 11 is shown the characters on the matrices in the magazine channels, numbered 0, 1 to 90, making 91 in all; the first channel, designated as 0, being the duplicate "e" channel.

In this figure the first line of characters below the diagram represent the characters that are cast when the matrices are in the lower or ordinary position. The characters in the line below represent the characters that are cast when the matrices are in the upper or auxiliary position, this being the standard arrangement of the small capitals in American line-casting machines, known to those skilled in the art, and the only one in general use in this country. Other arrangements, as for instance, the English, may be utilized, however, without departure from the scope of my invention. These secondary characters are positioned by "duplex rails" in the assembling and casting mechanisms which are old in the art and do not form a part of the present invention; their use is known by all operators.

The combinations of the blades for the last mentioned characters and the combinations for the cam rods of the magazine are such that there is no change affecting these characters when either shift blade 306 or 307, or both of these are shifted, but whenever the character key thereof is actuated the corresponding matrix of the magazine is discharged from its respective channel of the magazine.

For obtaining ligatures from the magazine no shift is required; it will be seen by referring to Table 1, that such characters are obtained by depressing two keys of the keyboard simultaneously, and in this manner the combination required is obtained and the matrix carrying two letters in a ligature. For example, the ligature "æ" is desired. It is found in column 89, (see Fig. 11). It is obtained by action of cam rods 3 and 4 required for "a" and cam rod 1 required for "e". (See vertical line 1, for "e" broken line 101, Fig. 11, and vertical line 3 for "a" broken lines 303 and 304, Fig. 11). By touching the two keys "A" and "E" at the same time, a different combination is controlled, and cam rods 101, 103 and 104, act to release a ligature matrix for "æ" from magazine channel 88. (See

Table 1—Continued

Table 1). Character "ff" is obtained by a special key.

Reference may now be had to Table 1.

While the form of the mechanism shown in Fig. 14 and Fig. 4 are technically described as a part of the invention, and the form shown in Figs. 17, 18 and 19 are described as a modified form; it is probable that the latter will be more generally used in the practice of

my invention, and considered as the preferred form thereof.

Key 1, h^1 , is blank, and controls weight 1, w^1 , which is provided with removable teeth, 5 1 to 7; and this may be changed to engage any desired combination of blades, which blades are not indented opposite said special weight. The blank key may be used in the manner described, singly or in a series, and the special 10 combination may be arranged at will by using weights with changeable or adjustable and removable teeth 1 to 7, and with blades which are not indented, or with blades having only a portion of the length thereof indented, and 15 the remainder thereof being unindented so that interchangeable teeth however disposed upon the weights, will engage the edge of each blade opposite which the tooth or teeth may be disposed. If desired all the weights may 20 be provided with interchangeable teeth and arranged so that they will selectively engage the edges of smooth blades in the required combinations. But it should be remembered that the shifting principle may be employed, 25 in all cases, whether the indented blades are employed, or interchangeable teeth upon the weights are employed to engage unindented blades. See Fig. 16.

While I have described and shown in the 30 foregoing specification and drawings forming a part thereof, forms and modified forms of the selective mechanism comprising my invention, particularly designed and adapted to be applied to typographical machines; I do 35 not wish to be understood as limiting myself thereto but reserve the right to depart therefrom within the scope and objects of my invention, which is to provide selective mechanism adapted for classifying all manner of 40 classified and differential objects and for performing various different functions, at the will of the operator at a keyboard or switch-board, by applying the principles and utilizing the elements, features, factors, and combinations shown and described in the above 45 and foregoing specification.

Having thus described my invention what I claim as new therein and desire to secure by Letters Patent of the United States is, 50 as follows:

1. Selective mechanism, comprising, a keyboard, a plurality of keys in the keyboard, a plurality of slides adapted for being actuated by the keys, one for each key; extensions on each slide, a plurality of blades, 55 adapted to be engaged by the extensions of said weights, one or more blades by each of said weight, a switch for completing an electric circuit whenever any one of said blades 60 is actuated; a plurality of cam rods, adapted for actuating releasing means for ejecting matrices from a magazine, said cam rods being held adjacent to said magazine; means for actuating the cam rods, in different combinations, so that each different combination

will control a release for a different matrix from the magazine, and means for transmitting movement from each of the said blades, 70 to one of the cam-rods, singly or in unison, so that with the movement of any blade or combination of blades, the corresponding cam rod or combination of cam rods will be actuated.

2. In a selective mechanism embodying a magazine containing a plurality of channels each having a plurality of matrices circulating therein; means for retaining and releasing said matrices, comprising a releasing pawl for each channel, a spring releasing member for actuating each pawl, and a plurality of cam rods adapted for moving singly or in combinations in unison for actuating the spring releasing means; clutch means for intermittently actuating the cam rods one clutch for each rod, magnetic means for releasing the clutches, and cam means for releasing the clutches after one rotation of a rod; a keyboard of a preferred layout, a plurality of selective blades adapted to be moved by the keys of the keyboard, singly or in combination, in unison; switches adapted for closing an electric circuit whenever any one of the blades is moved, said switches being adapted to act singly or in unison in combination; connecting wires leading from the switches to the electro-magnets, whereby the said magnets will be actuated, one by each of the said switches, singly or in unison, so that by the movement of any key of the keyboard, the movement will be imparted by the clutch mechanism from a single blade or a combination of blades to a corresponding single cam rod, or combination of cam rods, thereby actuating the releasing means of the channel containing the matrix corresponding with the character of the key actuated in the keyboard.

3. In a selective mechanism having a keyboard mechanism embodying a plurality of selectively movable blades controlled by the keys of the keyboard; a magazine mechanism embodying a plurality of cam rods, held in a frame adjacent a magazine, of the standard type employed in typographical machines; and means adapted to be actuated by the cam rods, for releasing matrices from the channels of the magazine; a clutch held in the frame adjacent each of the said rods, adapted for intermittently actuating said rods, a trip adapted for releasing said clutch said trip being so devised that the clutch will be released thereby whenever an electric circuit is closed, by the force of an electro-magnet; spring means for restoring the trip after it has been actuated; a continuously rotating gear adapted for being engaged by the clutch, adjacent each of said clutches, whereby the rod controlled by each clutch will be caused to rotate, whenever said clutch is engaged with said gear, either singly or in 130

unison in combination, and means for instantaneously stopping the rotation of each of said rods, when one rotation has been made; switch means for actuating the electro-magnets, provided upon the keyboard mechanism whereby each blade when actuated will close a circuit, whereby one of the said magnets, will be actuated, singly or in combination in unison with other magnets, so that movement is transmitted from each of said blades when actuated, through said switch mechanism to said clutch mechanism, to said cam rods, so that one cam rod will be actuated for each blade actuated, singly or in combination in unison with others.

4. In a selective mechanism, a plurality of cam rods, held in a frame adjacent a standard magazine, said rods being adapted to move intermittently singly or in unison so as to 20 actuate releasing means for releasing selectively any desired matrix from its respective channel of the magazine, when the key of the corresponding character, in the keyboard mechanism is actuated; keyboard mechanism embodying any preferred layout of keys, a plurality of blades adapted to be selectively moved by said keys, and corresponding in number with said cam rods; switch means for closing an electric circuit whenever one 25 of the blades is moved singly or in unison with other blades; electro-magnets, adapted to be actuated when said switches act to close the said electrical circuit, a magnet for each blade and each of said magnets being adapted 30 to release a spring actuated clutch whenever actuated, and each of said clutches serving to actuate one of the cam rods, when released by said magnet; a continuously rotating gear adapted for engagement with each of said 35 clutches, and cam means for disengaging each of said clutches from the rotating gear after one rotation of the cam-rod.

5. In a selective mechanism of the character described; a clutch adapted for intermittently engaging a rotating gear, and thereby actuating intermittently a rod connected with said clutch and rotatable therewith; and comprising a stub shaft, one end socketed in said rotating gear, and the opposite end journalled 50 in a suitable bearing and being recessed to receive an angular extension of the end of the cam rod connected therewith; a sleeve splined upon the stub shaft, and slidably thereon, clutch means upon one end of the 55 sleeve to engage the clutch means on the rotating gear; a pawl upon the sleeve which holds the clutch disengaged; a spring trip engaging said pawl, a spring at the opposite end of the sleeve from the clutch means which 60 normally holds the clutch in readiness for action when released by the spring trip, a differential cam in the said sleeve, which regulates the time in which the engagement is made, restores the sleeve releasing the clutch 65 and stops the rotation of the rod after com-

pleting one revolution, and an electro-magnet, adapted for actuating the spring trip and releasing the trip.

6. In a selective mechanism of the character described, clutch means for intermittently rotating cam rods, comprising; a stub shaft having one end shaped to receive the end of one of the cam rods, and to rotate said cam rod when it rotates, the opposite end thereof being socketed rotatably in a gear, said gear being journalled in a frame, and the opposite end of said shaft being journalled in another bearing in said frame; a 70 slideable sleeve splined upon said stub shaft; a spring adapted to throw the sleeve towards the said gear, clutch members upon the said gear and the adjacent end of the sleeve; a trip adapted to hold the said clutch disengaged, electric means for releasing the trip, a pawl on the trip and a groove in the sleeve adapted 75 to engage said pawl and prevent the sleeve from moving too suddenly towards the clutch; spring means for disengaging said pawl, so as to permit engagement of the clutch, a cam 80 roller and a differential cam groove, in the peripheral surface of the sleeve which serves to release the clutch and stop the rotation of the cam rod after one revolution thereof.

7. In a selective mechanism of the character described, an electro-magnetic trip for a clutch, comprising a core suitably wound, generating means and suitable connections whereby the circuit may be normally open and closed at will, suitable mounting means for the core and winding thereof; said core being formed at the end, adjacent the trip to be actuated thereby so as to present an arc-shaped surface to the arm of the trip, and the arms of said trip being formed so as to present an arc shaped surface to the core, 90 and having an extension closely adjacent the core when the circuit is open and the magnet inoperative, but which will not impact with the core before the whole surface thereof is engaged at the same time, thereby affording instantaneous magnetic action as soon as the circuit is closed by reason of the proximity of the extension of the arm of the trip, to the core.

8. In a selective means embodying a plurality of cam rods, said cam rods having differential cams thereon for actuating releasing means; spring releasing members, yieldingly held in a frame and adapted to act under their own spring power when the cam rods are rotated so as to release the spring releasing members, for actuating the releasing pawls of the magazine.

9. In a selective mechanism of the character described comprising a key board mechanism and a magazine releasing mechanism; rocking blades in the keyboard mechanism and means for selectively moving said rocking blades by the keys of the key board, and movable cam rods in the magazine mecha- 125

nism adapted to be selectively moved so as to release matrices from the magazine, switch mechanism connecting the keyboard mechanism and clutches for intermittently actuating the cam rods, said switch mechanism comprising, an arm held upon each of the rocking blades, and movable therewith, suitable electrical wires connected therewith and connected with an electro-magnet of the clutch mechanism, a universal bar, having a contact for engaging each of the arms of the rocking blades, a spring on each of said arms for yieldingly making the contact between the arm and the bar; said universal bar being slidably held in readiness to be brought into contact with an electrified contact post, connected with one end of a battery, the opposite pole of said battery being connected with the positive pole of the electro-magnet, whereby any one or any number of the rocking blades through said switch arms may be singly connected or connected in combination in unison with the electro-magnets of the clutches.

25 10. In a selective mechanism a cam rod movably held adjacent to a magazine, means for moving the cam rod, and a spring member adapted to be actuated by the movement of a cam of the cam rod.

30 11. In a selective mechanism a plurality of cam rods movably held adjacent to a magazine, means for moving the cam rods and a spring member adapted to be actuated by the movement of one or more of the cam rods,
35 singly or in combination in unison.

12. In a selective mechanism, a plurality of cam rods, a plurality of cams on each of said cam rods, means for actuating the cam rods, and a plurality of spring actuated members adapted to be actuated by the movement of one or more cams of the cam rods, singly or in unison in combination.

13. In a selective mechanism, a plurality of cam rods movably held adjacent to a magazine containing type matrices disposed in different channels, a plurality of spring actuated releasing members adapted to be actuated by the movement of one or more of the cam rods, and a series of paws, one for each channel of the magazine, adapted to be actuated for releasing a matrix from its respective channel when actuated by the spring releasing member.

14. In a selective mechanism, a pawl, pivotally held adjacent a magazine containing channels for matrices for type, each pawl being disposed within one of the channels, and having a weighted end with a tooth thereon adapted for engaging the ear of a matrix, and an extension upon its opposite end, adapted for engagement by a spring releasing means, and also adapted to engage the toe of a second matrix and an inclined surface on the extension adapted for engagement by the ear of said second matrix.

15. In a selective mechanism, a gravity controlled pawl, having a weighted portion with an engaging tooth thereon for engaging the ear of a matrix in the channel of a magazine, of a typographical machine, and a pawl upon its opposite end adapted for engaging the toe of a second matrix and an extension adapted for engagement by spring controlled or other actuating means, and an inclined surface on the under side of the extension adapted for being slidably engaged by the ear of the second matrix.

16. In a selective mechanism, a plurality of substantially U-shaped members of spring material held in inter-fitting relation having their ends rigidly secured in a frame, and held adjacent a magazine containing type matrices, and each having an extension thereon adapted for actuating a releasing pawl for the matrices in the channels of the magazine and a series of cam rods movably held in said frame and adapted to retain the said U-shaped members normally inactive, and when moved to release said U-shaped members, so that they may act by spring power, for actuating releasing pawls of the magazine so as to release a matrix from the magazine.

17. In a selective mechanism a suitable frame held adjacent a magazine containing circulating matrices in a series of channels, a series of movable cam rods removably held in said frame, a clutch sidably held upon an extension of each of said cam rods, a continuously rotating clutch member adapted for engaging each of said clutch members, means for retaining the clutches normally disengaged, electrical and spring means for actuating the clutches, and cam means for disengaging the clutches. 95

18. In a selective mechanism, a series of gravity pawls one being disposed in each channel of a magazine, containing circulating matrices, a plurality of spring releasing members, held in a frame adjacent the magazine and one being adapted to actuate each of said gravity pawls, a plurality of cam rods held in said frame and adapted to rotate singly or in unison in different combinations whereby the spring releasing members are actuated selectively, a clutch normally disengaged connected with each cam rod and electrical and spring means for engaging and disengaging the clutches, continuously rotating clutch members, one for each of said clutches, a plurality of switches arranged in a series and adapted to be actuated singly or in unison, for opening and closing electrical circuits, for the control of the electrical mechanism of said clutches; a plurality of blades movably held in a series in the frame of a keyboard mechanism, each of said blades supporting one of said switches, a plurality of pawls held movably in the frame of the keyboard mechanism, each having one or

more extensions thereon, and engaging each one or more of said blades, whereby said blades are movable, singly or in unison in combinations by said pawls and a plurality of keys each connected with one of said pawls, whereby said pawls are actuated to move the blades as aforesaid; specially formed blades shiftable in the frame, and adapted to be engaged differentially by the clutch extensions of said pawls, when in the normal position and the shifted position, whereby the movement of a certain key will actuate a different combination of the blades when in the shifted position; and special keys for controlling the shiftable blades.

19. In a selective mechanism of the character described, a plurality of blades, a plurality of pawls adapted to actuate one or more of said blades, and a plurality of blades shiftable longitudinally and having indentations thereon so that the said pawls will differentially actuate said blades when in the normal and shifted positions, a bearing on one of the blades, and a key for reversibly moving said blade thereby, and spring means for positioning the key; a bearing on a second shifting blade, and an extension thereon adapted for engaging the bearing on the aforesaid blade, so that when both blades are in the normal position, said extension will move the first blade to the shifted position when the second blade is shifted, and when both blades are in the shifted position, the bearing of the first blade will impinge upon the extension of the bearing on the second blade and move the second blade to the normal position with the first blade, and a key for reversibly moving the second blade, and spring means for positioning the key of the second blade, so that both blades may be moved to the shifted position singly by first touching the key of the first shiftable blade and thereafter touching the key of the second shiftable blade or both may be simultaneously moved to the shifted position by first touching the key of the second shiftable blade, and both blades may be moved from the shifted position to the normal position singly by first touching the key of the second shiftable blade and thereafter touching the key of the first shiftable blade, or both blades may be simultaneously moved from the shifted position to the normal position by first touching the key of the first shiftable blade, and adjustable means for regulating the thrust of the shiftable blades when shifted.

20. In a selective mechanism of the character described, having a plurality of movable blades, and a plurality of pawls adapted for engaging said blades whereby they are movable singly or in different combinations in unison, and keys adapted for actuating said pawls, a plurality of pawls with clutches fixed thereon or integrally formed therewith, for selectively engaging blades where some of

the blades are differentially indented, and a pawl or plurality thereof having clutches removably held thereon, for selectively engaging one or more of said blades, at a position thereon where there are no indentations in any of said blades, so that by removing the removable clutches from some of the pawls or by changing the clutches, they may be arranged so that the removable clutches on one of the pawls may engage and move any one or any combination of said blades when the pawl is actuated.

21. In a selective mechanism of the character described having a plurality of key-actuated blades, and a plurality of corresponding clutch controlled cam rods, a plurality of spring controlled clutches, normally open or disengaged, one clutch for each of said rods, and continuously rotating mating clutch members for rotating the clutches and the rods controlled thereby when in engagement, a plurality of electro-magnets, one for each of said clutches, adapted for magnetically actuating the releasing means whereby the clutches are released from their normally disengaged position so as to move into the engaged position, and switch mechanism connected with the aforesaid blades, one for each blade and wires electrically connecting the switch mechanism with the electro-magnets, so as to create a normally open electrical circuit, and when the blades or any of said blades are actuated by the keys, to close said circuit or any number of said circuits in unison in combination, so that movement may be imparted electrically from any one or any combination in unison of said blades through the corresponding switch mechanism to the corresponding one or combination of the electro-magnets in unison, so that any one or any number of the corresponding clutches, and the cam rods actuated thereby may be actuated singly or in unison in combination, corresponding with the movement of said blades.

22. In a selective mechanism, a clutch, slidably held upon a shaft normally at rest but rotatable with the clutch, said clutch being normally at rest and disengaged, continuously rotating clutch members for engaging the slideable clutch, a cam member disposed in a differential annular channel in the slideable clutch, adapted for stopping the rotation of the slideable clutch and releasing the same after engagement of the clutch, and a second annular channel at a spaced distance from the differential annular channel, a pawl or post on the clutch adjacent the differential annular channel, and a pawl having two arms, one normally holding the said pawl or post, and a second arm adapted for engaging the second annular channel, means for actuating the pawl so that said second arm will engage the second annular channel and release the first arm from engagement with the said pawl or post adjacent to the differ-

ential annular channel; thereby releasing the 10
slidable clutch; spring means adapted for
moving the slideable clutch into engagement
with the continuously rotating clutch members,
and means for restoring the pawl for re-
taining the slideable clutch in disengaged rela-
tion after one rotation thereof.

23. A clutch slidably held upon a shaft
normally at rest but rotatable with the clutch,
10
said clutch being normally at rest and dis-
engaged, continuously rotating clutch members
for engaging the slideable clutch, a cam
member disposed in a differential annular
15
channel in the slideable clutch adapted for
stopping the rotation of the slideable clutch
and releasing the same after engagement of
the clutch, and a second annular channel at
a spaced distance from the differential annular
20
channel, a pawl or post on the clutch
adjacent to differential channel, and a pawl
having two arms, one normally holding the
said pawl or post and a second arm adapted
for engaging the second annular channel,
means for actuating the pawl so that said
25
second arm will engage the second annular
channel and release the first arm from en-
gagement with the said pawl or post adjacent
to the differential annular channel; thereby
releasing the slideable clutch; spring means
30
adapted for moving the slideable clutch into
engagement with the continuously rotating
clutch members, and means for restoring the
pawl for retaining the slideable clutch in dis-
engaged relation after one rotation thereof.

24. In a selective mechanism of the char-
acter described having a plurality of selective
cam rods, comprising a part of a magazine
unit, a plurality of clutches, one for each of
the said cam rods, and comprising a part
40
of a transmission unit, and a plurality of
selective blade elements, comprising a part
of a keyboard unit, and a plurality of spring
actuated tripping pawls adapted for releas-
ing the said clutches, and means whereby a
45
movement of one or more of the blade ele-
ments will release one or more of the trip-
ping pawls, singly or in unison in combina-
tion.

25. In a selective mechanism of the char-
acter described, having a magazine unit, a
transmission unit and a keyboard unit, a
plurality of normally open clutches in the
transmission unit, and a plurality of trip-
55
ping pawls, normally holding said clutches
in open relation, a plurality of blade ele-
ments in the keyboard mechanism, and a plu-
rality of crank elements, one for each of the
blade elements, and means whereby the trip-
ping pawls may be actuated singly or in uni-
60
son in combination when the blade elements
are actuated singly or in unison in combina-
tion.

26. In a selective mechanism of the char-
acter described, a magazine unit embodying

70
a series of releasing pawls, and a series of
cam rods for actuating the releasing pawls;
a series of clutches for actuating the cam
rods, and a series of tripping pawls for trip-
ping the clutches, a keyboard unit embody-
ing a plurality of selective blades and means
whereby the tripping pawls may be actuated
singly or in unison when the said blades are
actuated.

27. In a selective mechanism having a key-
board arranged and combined so that each
75
of the keys when actuated will actuate the
selective mechanism so that a matrix carry-
ing a certain character will be released from
the magazine of the mechanism, and means
whereby a ligature will be released from said
80
magazine when ever the keys representing
the characters of said ligature are actuated
simultaneously.

28. In a selective mechanism having a key-
board, arranged and combined so that each
85
of the keys when actuated will actuate se-
lective mechanism so that a matrix corre-
sponding with the key actuated may be re-
leased when the key is actuated; means
whereby the ligature "ff" or the ligature
90
"ffi" may be released when the key design-
ated as "ff" is actuated in unison with the
key "i" or "l" respectively.

29. In a selective mechanism, in which
95
permuted rods are employed for selectively
releasing matrices from a magazine, a plu-
rality of keys each designated by a word,
sign, or character, and each key arranged
100
and adapted to control one or more of the
permuted rods, singly or in combination; and
means actuated by said rods whereby a type,
matrix or character corresponding with the
character of the key actuated will be ac-
tuated or controlled or released.

30. In a mechanism employing a series of
differential units or matrices, designed or ar-
ranged according to the use or class thereof,
by letters, figures, or other characters or
means, mechanism for controlling the said
110
matrices or units including a keyboard
mechanism, means for connecting a keyboard
of the style of the standard typewriter or any
preferred layout with releasing means of the
mechanism for controlling matrices or differ-
115
ential units when arranged in the manner and
style used in the standard linotype machine
or any preferred form of magazine or order
and style of arrangement, whereby the keys
of the keyboard will release or control the
120
matrices or units described, corresponding
with the character of the key actuated, un-
limited by the location of the said matrix or
unit in the machine or magazine thereof, and
adjustable means whereby one set of keys of
125
an alphabet may be employed for lower case
letters, capital letters, and or small capital
letters, and a group of said set of keys may
be employed to release or control the matrices
or units of figures, spaces, points and mis-
130

cellaneous characters or classes of such matrices or units regardless of the change in the adjustment of the mechanism above described.

- 5 31. In a selective mechanism a set of type matrices or differentiated units, means for releasing or controlling the same for practical use, a series of movable members movable singly or in any combination, said members being adapted when so moved to actuate the releasing or controlling means for a single matrix or unit a second series of movable members movable singly or in any combination, each of the second series being directly 70
10 or indirectly related to one of the first series 75
15 of movable members, so that when one of the movable members of the second series is moved the co-related movable member of the first series is simultaneously moved; a 80
20 series of members each having a series of elements adapted to actuate one or more of the second series of the movable members; and a keyboard of any preferred layout, each key being adapted for actuating one of the members 85
25 which actuate the second series of movable members, whereby a matrix or unit corresponding with the key actuated will be released or controlled, unlimited by the layout 90
30 of the keys of the keyboard or the order and arrangement of the matrices or differentiated units in the mechanism, and unlimited by 95
35 the relative extent or size of the keyboard or the mechanism for releasing or controlling the matrices or other units, and unlimited in its operation by the relative position of 100
40 the keyboard to the other parts of the mechanism, and means for adjusting the mechanism whereby the keys which release or control the respective matrices or units of an alphabet may serve to release or control another class thereof, whereby the same keys, by adjustment of the mechanism may be employed to release or control capital letters, lower case letters and/or small capital letters. 105
45 32. In a selective mechanism employing a series of differential matrices or units designed or arranged according to the significance, function or use thereof by letters, figures, or other characters or differentiating 110
50 means, all arranged and disposed in the mechanism and held in readiness to be employed and used when released or controlled at the will of an operator by means of a keyboard and co-related mechanism; a series of 115
55 releases one for releasing and controlling each matrix or unit singly; a series of movable members adapted to move singly or in any combination adapted for actuating the said releases singly when any one or any 120
60 combination thereof is moved; a second series of movable members, each connected directly or co-related with one of the first series of movable members, so that when one or any combination of the second series is moved, a 125
65 corresponding one or combination of the first

series will be moved simultaneously; keyboard mechanism arranged and devised so that when any key is actuated certain of the first and second series of movable members act simultaneously thereby actuating the means for releasing or controlling one of the matrices or units which corresponds with the key actuated, and adjusting means whereby one key or set of keys may be utilized for releasing or controlling two or more classes of matrices or units, and means for using a keyboard of any size or style of layout, or disposed in any preferred relation to the other parts of the mechanism, and unlimited by the arrangement, number, or size of the matrices or other units, or the other parts of the mechanism. 75
80

33. In a typographical machine, a matrix escapement pawl with a weighted portion, the inertia and momentum of which serve to time the action of the escapement. 85

34. In a typographic machine, selective mechanism, including a keyboard mechanism adapted to close a plurality of electric circuits in various combinations, in each circuit an electromagnet for actuating a one-revolution clutch which serves to connect with a common source of power one of a plurality of shafts with cam surfaces permuted thereon, said cam surfaces locking or unlocking a 90
95 plurality of escapement mechanisms. 95

35. In a typographic machine having a keyboard with a single alphabet, shifting means for utilizing supplemental alphabets, comprising notched rocking blades shiftable 100
105 longitudinally.

36. Selective mechanism, comprising a keyboard containing a plurality of slides actuated by keys, a plurality of blades adapted to be engaged by said slides selectively in various combinations and each adapted to close an electric circuit, a plurality of permuted cam members in juxtaposition to a typographic magazine, each controlled by one of said electric circuits, said cam members directly controlling escapements in said magazine. 110

37. In a typographical machine in which characters are obtained by permuted cam bars used in various combinations, means for using a combination for a ligature or diphthong that is the sum of the combination of its component letters. 115

38. In a typographical machine in which characters are obtained by permuted cam bars used in various combinations, means for using a combination for the ligature "ff" which is the sum of the combinations used for "ff" and "i". 120

39. In a typographical machine in which characters are obtained by permuted cam bars used in various combinations, means for using a combination for the ligature "fff" which is the sum of the combinations used for "ff" and "l". 125
130

In testimony whereof, I, ROY EMERY, have signed my name to this specification, this eighth day of September, 1925.

ROY EMERY.
